UNITED STATES PATENT OFFICE.

OLIVER C. RITZ WOLLER, OF CHICAGO, ILLINOIS.

DESIGN FOR A COMBINED LIGHT AND LICENSE-PLATE HOLDER.

Application filed November 7, 1925. Serial No. 15,378. Term of patent 14 years.

To all whom it may concern:

Be it known that I, OLIVER C. RITZ WOLLER, a citizen of the United States, residing at Chicago, in the county of Cook and State of Illinois, have invented a new, original, and ornamental Design for Combined Light and License-Plate Holders, of which the following is a specification, reference being had to the accompanying drawing, forming part thereof.

Figure 1 is an elevation of the combined

light and license plate showing my new design.

Figure 2 is an end view drawn on a reduced scale.

I claim:

The ornamental design for a combined light and license plate holder, as shown.

In testimony whereof I affix my signature at 10 South La Salle Street, Chicago, Illinois.

OLIVER C. RITZ WOLLER.
